UNITED STATES PATENT OFFICE.

CHREST LIMPEROS, OF WILMINGTON, DELAWARE.

DESIGN FOR A DIRECTING SIGNAL FOR AN AUTOMOBILE.

Application filed January 28, 1925. Serial No. 12,164. Term of patent 3½ years.

To all whom it may concern:

Be it known that I, CHREST LIMPEROS, a citizen of the United States, residing at Wilmington, in the county of New Castle and State of Delaware, have invented a new, original, and ornamental Design for a Directing Signal for an Automobile, of which the following is a specification, reference being had to the accompanying drawing, forming a part thereof.

Figure 1 is the front view of a directing signal for an automobile, and

Figure 2 is a side elevation.

What I claim is:

The ornamental design for a directing signal for an automobile, as shown.

CHREST LIMPEROS.
